PUMP VALVE

John C. Enders, St. Louis, Mo., assignor of one-fourth to Monroe P. Lambert and one-fourth to George B. Jaycox, both of St. Louis, Mo.

Application June 19, 1934, Serial No. 731,354

1 Claim. (Cl. 251—127)

This invention relates to pumps and particularly to those pumps in which there is a standing valve at the lower end of the pump cylinder and a valve in the piston opening upon the movement of the piston toward the standing valve and closing upon the reverse movement of the piston.

The general object of the present invention is to provide a pump in which the piston is not directly and rigidly connected to the piston rod, but in which the valve is connected to the piston rod and the piston has a slight movement with relation to the piston rod so that upon an initial movement of the piston rod in one direction, the rod will move relative to the piston to open the port through the piston and upon a reverse movement of the rod, the valve carried by the rod will close the port opening of the piston and then pick up the piston and move it.

A further object is to provide a construction of this character in which the valve mechanism of the piston may be made interchangeable with the standing valve, thus cheapening the construction of the pump.

A further object of the invention is to provide a piston or plunger or valve that is simple in construction, efficient in operation, has a long life, may be easily replaced and has a small number of parts.

Other objects will appear in the course of the following description.

My invention is illustrated in the accompanying drawing, wherein:—

Figure 1 is a longitudinal section through a pump cylinder showing the piston and standing valve in section;

Figure 2 is a top plan view of the guide used in connection with the valve.

Referring to the drawing, A designates any usual or ordinary pump cylinder and B and C the opposite heads of the cylinder. The head B is, of course, provided with the outlet D and the head C with the inlet E. As illustrated, the head C is provided with a valve seat 13 resting upon a gasket 11. This seat is disposed within the bowl-shaped portion 12 of the head C and is provided with the inwardly extending annular flange 13 which constitutes the seat proper of the valve. The standing valve is designated 14 and is provided with a central solid portion normally resting upon the seat 13 and provided at its margin with a plurality of passages or apertures 15. This valve is shown as having the stem 16 extending downward through the seat 13 and pinned or otherwise attached to a guide 17 having a central portion embracing the stem 16 and having an

outwardly and upwardly inclined annular flange 18 formed with a plurality of perforations 19.

It will be seen that the guide 17 is movable toward or from the under face of the seat 13 as the valve 14 moves toward or away from the seat 13. This element 17 acts as a guide for the valve and slides within a recess 20 formed in the lower end of the sleeve element 10.

Upon the up stroke of the piston, the valve 14 and the guide 17 rise, permitting liquid to pass upward through the apertures 19 and around the valve 14 into the body of the cylinder. Upon a downward movement of the piston in the cylinder, the valve 14 is closed as usual.

The piston rod 21 has pinned, screwed or otherwise attached to it at its lower end the valve 22. This valve is rigid on the piston rod and is disposed within a recess 23 formed in the under face of the piston or plunger 24. The piston 24 has a large aperture in the center designated 25 through which the piston rod 21 freely passes. The valve 22 has a portion 26 seating against a seat formed on the under face of the piston 24 immediately surrounding the opening 25 and outward of this seat 26, the valve 22 is formed with apertures 27.

The upper face of the piston is recessed at 28 and disposed within this recess is the guide 29 which has the same form as the guide 17, that is, it is provided with a central hub portion and an outwardly, and in this case downwardly, extending flange 30 formed with apertures 31. This member 29 is loose upon the piston rod 21 but is retained in place within the recess 28 by means of a spring 32 surrounding the piston rod, bearing against the hub of the valve 29 and at its upper end bearing against a collar 33 pinned to the piston rod.

In the operation of this valve, upon the up stroke of the piston rod, the piston 24 will be drawn upward by its engagement with the valve 22, but upon the downward movement of the piston rod, the piston rod with the valve 22 will move downward a predetermined amount, the valve 22 leaving its seat 26, the piston remaining stationary until the collar 33 has compressed the spring 32 sufficiently to cause the guide 29 to move downward and carry with it the piston 24. The first initial movement of the piston rod, therefore, opens the valve and then a further movement depresses the piston or plunger 24. Upon the return stroke, the piston rod and the valve 22 rise, the piston remaining stationary until the valve seats against the piston and then

the piston and the allied parts rise with the piston rod.

For the purpose of opening the valve 14 in order to drain the pump, as for instance, in cold weather, I have provided a lifter 34 mounted upon a shaft 35 extending transversely through the head C and provided upon its exterior end with means whereby it may be rotated. Thus the standing valve may be readily lifted.

While I have illustrated a particular form of pump cylinder with detachable heads, the heads being bolted to each other, I do not wish to be limited to this particular form of pump body as this is merely illustrative. This structure may be used for air pumps or liquid pumps. The purpose of providing the spring 32 is to secure a cushion upon the downward stroke of the piston and relieve the shock or jar which would be incident to the collar 33 striking the upper end of the guide 29. This spring, therefore, prevents back lash or jerk at the reverse stroke of the piston rod and acts to return the valve to its seat after downward pressure has been removed.

It will be noted also that the valve 22 is guided to its seat by its peripheral contact with the wall of the recess 23 instead of being guided to its seat by small pins as is usual in pumps of this character. This means that inasmuch as the periphery of the valve has more metal to wear, the valve will have a longer life.

It is particularly to be noted that the lower valve or standing valve is an exact reproduction of the plunger valve. The stem 16 may be screw-threaded into the valve head 14 in the same manner as the pump piston is screw-threaded into the valve head 22. The guide 29 is of the same character as guide 17 and these guides may be used indifferently either upon the piston 21 or upon the valve stem 16. It will be seen that the seating element 10 is an adaptor which may be used in pumps for the purpose of permitting the use of the guide 17 and of the valve 14.

While I have illustrated a pump in which liquid is taken in at the lower end of the cylinder upon the upstroke of the piston and the liquid discharged from the spout D upon this up-stroke,

yet it will be obvious that by reversing the piston 24, that is, inverting it from the position it has in Figure 1 and reversing the valve 14 and the guide 17 and, of course, reversing the valve seat, the pump will then draw in fluid through the head B and expel fluid through the head C, that is, the direction of flow of fluid through the pump is reversed so that the discharge is on the pushing stroke instead of upon the pulling stroke as shown in the drawing. This is particularly necessary in such pumps as are used for tire pumps and in many other different circumstances.

It will thus be seen that I do not wish to be limited to the arrangement of the piston and standing valves as shown in my Figure 1 as this arrangement may be inverted or reversed and that when inverted or reversed, the valves will operate in the same manner as described except that the valve 14 will open upon the down-stroke of the piston and the valve 22 will close upon the down-stroke of the piston.

The valves which I have shown are intended as much for replacement for pumps already in use as they are for installation of new pumps.

While I have illustrated certain details, I do not wish to be limited thereto, as it is obvious that modifications might be made without departing from the spirit of the invention as defined in the appended claim.

I claim:—

In a pump, an element having a central axial passage, the element being recessed on its opposed faces concentric to the axial center of the element, the inner wall of one of said recesses being formed to provide a valve seat surrounding the central passage, a valve having a sliding fit within one of said recesses and coacting with the valve seat, the valve having marginal apertures, a central stem on which the valve is carried extending through the passage in the element, and a guide mounted on the stem and fitting within the other of said recesses and engaging the wall thereof, the margin of the guide being apertured, the guide constituting a stop limiting the opening movement of the valve.

JOHN C. ENDERS.
